UNITED STATES PATENT OFFICE.

ALBERT C. FISCHER, OF CHICAGO, ILLINOIS.

ROOF COVERING.

Application filed August 16, 1920. Serial No. 403,894.

To all whom it may concern:

Be it known that I, ALBERT C. FISCHER, a citizen of the United States, residing at Chicago, in the county of Cook and State of Illinois, have invented certain new and useful Improvements in Roof Coverings, of which the following is a specification.

This invention relates to coverings in the form of strips or shingles adapted to protect 10 roofs or sides of buildings and the coverings are composed of thin strips of more or less flexible material adapted to withstand the action of the weather when exposed as a covering on such structure.

15 The strips are laid to form horizontal courses, the lower edge of each shingle or strip of shingles overlapping the upper edge of the next strip or row of shingles below it. The shingles or strips of shingles are 20 preferably made of a fibrous material compressed and treated to render same water proof whereby it is rendered capable of withstanding the heat from the sun and the weather action and may also by the use of 25 suitable fire proof ingredients be rendered free from liability of ignition by sparks falling on the roof.

It has heretofore been proposed to form shingles or strips of roofing material as a 30 protective roof covering from compressed fibrous material and such shingles or strips have heretofore been made in a great variety of forms exposing ends thereof when laid in roof formation, which are of rectangular 35 or other desired shapes. In such roofs it has heretofore been a difficult matter to prevent the exposed shingle ends from blowing up and curling as no suitable method has heretofore been devised by which the exposed 40 ends or shingle tabs may be held down.

It is therefore the primary object of my invention to provide a roof covering made up of shingles or shingle strips provided with interlocking means for preventing the exposed 45 ends or tabs of the shingles or shingle strips from curling or blowing up due to the action of wind or sun whereby the exposed ends or tabs of the shingle will be separated from the underlying course or courses.

50 It is a further object of the invention to provide a form of shingle or strip of shingles which are self spacing or which have the desired spacing indications thereon for marking the proper spacing of the shingles 55 from each other laterally or in the direction of the length of the course.

Other objects of the invention will appear from the description of the preferred embodiments of the invention which are depicted in the accompanying drawings forming a part of the specification, the novel features being set forth in the appended claims.

In the said drawings Fig. 1 is a fragmental or broken portion of a roof showing 60 a plan view of same.

Figs. 2 and 3 are sectional views on lines 2-2 and 3-3 of Fig. 1.

Fig. 4 is an enlarged fragmentary plan view similar to Fig. 1 showing in greater 70 detail the manner in which the tab ends of the shingles are secured when formed of strips similar to the constructions shown in Figs. 5 to 8 inclusive.

Fig. 5 is a plan view showing two strips 75 interlocked together, the view being taken from the normal reverse side of the interlocked strips.

Fig. 6 is a perspective view of the border strip of Fig. 5 applied to a supplemental 80 covering strip which is preferably used in laying the first course of the roofing next to the lower edge of the roof.

Fig. 7 is a perspective view similar to Fig. 6 showing the application of the first 85 strip of shingles with interlocking means thereto and Fig. 8 shows in perspective the strip of Fig. 7 in process of attachment, attached and secured to the roof.

Fig. 9 is a perspective view of an individual shingle provided with the interlocking means for holding down the tab ends as shown in Figs. 1 to 4 inclusive and also in Figs. 7 and 8.

Fig. 10 is a fragmentary plan view of a 95 roof constructed of individual shingles of the form shown in Fig. 9.

Fig. 11 is a perspective view of a shingle showing the interlocking means slightly modified over the form shown in Fig. 9.

Fig. 12 is a plan view of an individual shingle having the interlocking means for the tab end of the shingle formed separately therefrom and attached thereto, and Fig. 13 is a transverse sectional view on line 13-13 105 of Fig. 12.

The views of the roof shown in Figs. 1 to 3 inclusive are illustrative of a roof formed of my improved form of interlocking shingle, whether it be of the individual type 110 of Figs. 9 and 10 or whether it be formed in courses or strips as illustrated in Figs. 5 to

7 inclusive. Reference character 10 of Fig. 9 illustrates the body portion of a shingle rectangular in form and preferably cut from a sheet of suitable water proof material as 5 felt or paper saturated with water proofing material such as asphalt, pitch or the like, and having cut from the body thereof the interlocking means which forms one of the important features of my invention. This 10 interlocking means is formed by cutting near the tab end or normally exposed end of the shingle two transverse slots 11 and 12 extending from the longitudinal edges of the shingle toward each other but not 15 quite meeting so as to leave a narrow flexible neck portion 13 joining to the shingle an interlocking head composed of lateral extensions 14, 15, which head is permitted by the flexible neck to be bodily depressed 20 from the plane of the shingle of the succeeding row, which carries it, to a plane beneath two spaced shingles of the antecedent row, which are bridged. In applying the shingle of Fig. 9 the roof will first 25 be provided with a suitable sheathing or covering as of wood or other suitable material, as indicated by reference character 16, Figs. 2 and 3. At the lower or trough edge of the roof there will be preferably first 30 provided a sheet of suitable water proof material that may be of any desired width so as to underlie one or more courses of the shingles 10, such a strip being designated by reference character 17, Fig. 6. Following 35 the application of the strip 17 I next lay a course of shingles 10 in the ordinary manner with a spacing between adjacent shingles sufficiently narrow to sustain the bridging shingles in a plane above them. 40 These shingles on the first course will preferably have the neck portion 13 and the interlocking heads 14 and 15 clipped from the bodies of the shingles leaving them perfectly plain in form, as indicated by reference 45 character 10^a, Fig. 10, since it will be obvious that the interlocking extensions 14 and 15 would not function upon the lower-most course of the roof. In the application 50 of the plain shingles 10^a to the first course the spacing between adjacent shingles will be regulated according to the width of the neck portion 13 on the shingles 10 so that when the plain shingles 10^a of the first course are fastened to the roof sheathing or 55 foundation by nails or other suitable retaining devices, as indicated by reference character 18, Fig. 10, the interlocking heads 14, 15 of the succeeding row of shingles can be introduced as suggested in Figure 7, and 60 brought to the positions indicated in Figures 1 to 5, 8, and 10, and then nailed or otherwise secured, as indicated at 19, and other and succeeding overlying courses of shingles may be applied in the same manner 65 until the roof is completed.

In the form of shingle shown in Fig. 11 the extensions which form the interlocking head are slightly modified as indicated at 14^a and 15^a by being shortened over the 70 form of Fig. 9 and cut at an angle as indicated, which renders their application beneath the preceding courses of shingles somewhat easier, although the shingles of the form of Fig. 11 are applied and the 75 interlocking devices thereon function precisely as the corresponding parts on the preferred form of Fig. 9. It will be noted in both forms of shingle of Figs. 9 and 11 that the spacing between individual shingles will be determined by the width of the neck 80 portion 13, which will be uniform in each shingle desired for a particular installation and will for symmetrical purposes be about the relative width of the neck portion illustrated in Figs. 9 and 10, which will result 85 in a finished roof having the appearance of that illustrated in Fig. 1.

In Fig. 8 the body portions of the shingles 10 are shown formed in connection with an integral strip of material designated by reference character 20, the tab ends of the shingles 10 being provided with the integral interlocking heads 14, 15 connected to the body, part of the shingles 10 by the neck 90 portions 13. When the shingles are formed 95 in continuous strips, as illustrated in Figs. 7 and 8 their application is more economical as the strips may be formed in any desired lengths, and thus a plurality of shingles may be handled collectively. Moreover, by drawing 100 an upper strip upward until the necks 13 bring up against the integral strip next below, row-spacing is accurately effected, and the row being laid is justified in its 105 position, parallel with the antecedent row. When in strip formation at the bottom or lower edge of the roof an underlying strip 17 of suitable waterproof material will first 110 be applied as explained in connection with shingle of Fig. 10 (Figs. 6 to 8 inclusive) and the interlocking necks 13 of the first course will preferably be clipped off to form the first row of shingles 10^b as indicated in Figs. 5 to 8 inclusive. Thereafter the application 115 of the strips will be precisely as in the case of the individual shingles, the edges of the tabs 10^b being raised to allow the insertion of the interlocking portions 14 and 15 thereunder, Figs. 5, 7 and 8, and when the strip 120 and the interlocking portions are in proper position the strips will be nailed down or otherwise secured as indicated at 21, Fig. 8. Suitable fastening means will also be used 125 as well understood for securing the strip 17 and the first strip comprising the shingles 10^b (as indicated by the nails 30, Fig. 7).

In Figs. 12 and 13 is shown a modified form of the shingle of Fig. 9, the body part of the shingle indicated by reference character 10^c being formed precisely like the 130

body part 10 of Fig. 9 of a rectangular form and having a metallic retaining or locking device with a neck 33 similar to the neck 13 of the shingle of Fig. 9 and with interlocking heads comprised in extensions 34, 35 thereon which function precisely as the extensions 14 and 15 of the shingle of Fig. 9. This attached part will preferably have a widened portion 35^a at the extremity of the neck 33 by which same may be riveted, as indicated by reference character 36, Fig. 12, or otherwise suitably attached to the body 10^e. In the application of the shingle of Figs. 12 and 13 no change is made over the application of the similar shingle of Fig. 9.

While I prefer the form of shingle illustrated in Fig. 9 it will be obvious that the modifications of the invention as shown in Figs. 11 to 13 may be used to advantage and when any of these forms is employed it will be seen that the interlocking of the tab ends of the shingles will be so complete with respect to each underlying course that the raising or curling of any of the tab ends of the shingles will be rendered almost impossible or at least very unlikely, which will result in a roof that will be practically impervious to moisture and will endure in this condition for a long time as it will not be susceptible to corrosive or rotting effects of the elements when properly prepared of well known fire proofing materials and by reason of the described characteristics it will avoid many, if not all, of the objections which have been urged against roofing materials of a similar character as heretofore constructed.

I claim:

- 40 1. In felt roofing, an antecedent course of closely spaced shingle-like roofing members, and a succeeding course of shingle-like roofing members bridging the spaces between the members of the antecedent course and supported thereby in a plane above that of said antecedent course; the members of the succeeding course being constructed on their lower edges with interlocking heads connected with said members by narrow flexible necks that permit the heads to be bodily depressed from the plane of the course which carries them downwardly to a plane beneath the members of the antecedent course.
- 55 2. In felt roofing, an antecedent course of spaced shingle-like roofing members, and a succeeding course of shingle-like roofing members bridging the spaces between the members of the antecedent course and supported thereby in a plane above that of said antecedent course; the members of the succeeding course being constructed on their lower edges with interlocking heads connected with said members by narrow flexible necks that permit the heads to be bodily

depressed from the plane of the course which carries them downwardly to a plane beneath the members of the antecedent course; spaces between the members of the antecedent course being closed at their upper ends to arrest the upward movement therein of the necks of the succeeding course and thereby determine the position of the succeeding course with reference to the antecedent course.

3. In felt roofing, an antecedent series of shingle-like members, a connecting portion uniting said members in a course with spaces between them, a succeeding series of shingle-like members overlapping the antecedent series and provided upon their lower ends with interlocking heads adapted to underlie adjacent edges of the spaced members of the antecedent series, and flexible necks connecting said heads, corresponding in width with the spaces between the members of the antecedent series; the members of the succeeding series being united in fixed spaced relation with their necks at distances apart to correspond in position with the spaces between the members of the antecedent series, and said necks having a dimension which permits them to reach from the plane of the succeeding series of members which carries them, to the plane beneath the members of the antecedent series under which the interlocking heads lie.

4. In felt roofing, an antecedent series of shingle-like members, a connecting member uniting said members in a course with shingle spaces between them, said spaces being open at their lower end but closed at their upper ends by means of said connecting member, a succeeding series of shingle-like members overlapping the series first named and constructed upon their lower ends with flexible necks corresponding in positions to the spaces between the members of the antecedent series, and interlocking heads carried by said necks, adapted to enter beneath the edges which define said spaces; said heads being adapted, by encountering the closed ends of the slots, to determine the position of the succeeding series upon the antecedent series.

5. A roof covering comprising a strip of material having transverse slots intersecting the same from one longitudinal edge thereof toward but not reaching the opposite longitudinal edge, thereby forming a series of united shingle-like tabs; said tabs having each upon the free end thereof a flexible neck portion and an interlocking head at the end of said neck portion; the distance between neck portions corresponding to the distance between slots and the necks being restricted in width within the width of the slots so that with a plurality of strips the interlocking heads on the tabs of an overlying strip will enter beneath the edges which define the

- slots of an underlying strip, and the necks can be deflected from the plane of the overlying strip to a plane beneath the underlying strip.
6. Flexible strip roofing comprising courses of spaced shingles having the shingles of each course united by a portion of the strip extending transversely of the shingles, the courses being adapted to be laid 25 with the shingles of a succeeding courselapping those of an antecedent course and covering the spaces between them, the shingles of the succeeding course being provided with slots extending laterally inward from 30 their side edges, that permit lateral portions of the shingles of the antecedent course to overlap those portions of the succeeding course which lie below the slots and to underlie those portions of the succeeding 35 course which lie above the slots.
7. Flexible strip roofing comprising courses of spaced shingles having the shin- 40

gles of each course united by a portion of the strip extending transversely of the shingles, the courses being adapted to be laid 25 with the shingles of a succeeding courselapping those of an antecedent course and covering the spaces between them, the shingles of the succeeding course being provided with slots extending laterally inward from 30 their side edges, that permit lateral portions of the shingles of the antecedent course to overlap those portions of the succeeding course which lie below the slots and to underlie those portions of the succeeding 35 course which lie above the slots; the length of the slots being such as to leave between their opposed inner ends, necks corresponding in width and position to the spacing of the shingles upon the connecting strips.

In testimony whereof I have signed my name to this specification on this 6th day of August, A. D. 1920.

ALBERT C. FISCHER.
